DOORSTOP AND HOLDER

Vincent Iarobino, Long Island City, N. Y.

Application September 27, 1939, Serial No. 296,728

6 Claims. (Cl. 292—138)

This invention relates to a doorstop and door holder.

An important object of my invention is to provide a device located remote from the plane of a door opening and which is operable by the opening and closing movement of the door mounted therein, whereby the said device is adapted to serve, at the will of the operator, as a doorstop or door holder.

Another important object of my invention is to provide a device of the class described which is adapted to be mounted level with the surface of the floor proximate the door with which the same is operably associated or connected so as not to present an obstruction of any kind over which one may trip or stumble when the door is closed.

A further object of my invention is to provide a device of the class described suitable for use in connection with schoolroom doors which device is so constructed that the same is not readily accessible to one desiring to tamper therewith and at the same time simple and inexpensive to construct and install.

Further objects and advantages of my invention will be hereinafter referred to or become apparent from the following description thereof written in connection with the accompanying drawing, in which

Figure 1 is a plan view of my device with certain parts removed and others broken away to show the channel member and trigger rod mechanism extending between the doorstop and its control mechanism.

Figure 2 is a sectional elevational view of my device taken on line 2—2 of Figure 1 and looking in the direction of the arrows, and shows the same permanently mounted beneath the surface of the floor proximate a door and doorway with which the same is to be used.

Figure 3 is a view taken on line 3—3 of Figure 1 and looking in the direction of the arrows, showing in full lines the manner in which the door may be engaged by the door holder, and in dotted lines the manner in which the mechanism serves as a doorstop.

Figures 4 and 5 are detail views taken on lines 5—5 of Figure 1 looking in the direction of the arrows showing the door and associated mechanisms in both operative and inoperative positions.

Referring now to the drawing, it will be seen that my device comprises a rod 10 mounted in any suitable housing or casing, such for example as in a channel 11 having a cover 12 adapted to be suitably secured thereto for reasons to be

hereinafter described. The rod 10 serves as a motion transmitting means and extends from a point within a trigger box 13, secured in any suitable way to one end of a channel 11, to a bolt socket 14 similarly secured to the other end 5 of said channel. In the embodiment of my invention here shown both the socket 14 and the box 13 are provided with ears 15 by which they are bolted, riveted or otherwise suitably secured to the channel 11. The bolt socket 14 is closed 10 at the bottom, as at 16, and the trigger box 13 is provided with an upper cover 17 and a bottom plate 18. Both the cover 17 and the plate 18 are removably secured to the box 13 in any suitable way and are adapted to be interchangeably 15 secured to the top or bottom of the box for reasons to be hereinafter stated. It is to be noted, however, that the box 13 in the embodiment shown, extends to one side of the channel 11. One end of the rod 10, referred to above, extends 20 into the box 13 through a vertically elongated opening or slot 19 formed in the side thereof at a point between the ears 15.

A plate 20, having a pair of parallel ribs 21 is slidably mounted in grooves within, and at 25 one end of, the box 13, which grooves are formed by means of guide strips 22 disposed respectively on the sides of the box at a point spaced from the inner surface of one end of the box and parallel thereto. It will be understood that the 30 plate 20, and either end thereof, may be inserted into the box 13 from either side thereof, for reasons to be hereinafter explained. A lever 25, having one end 26 pivoted between the ribs 21 and the other end 27 operatively engaging the 35 rod 10 is adapted to operate the rod through the medium of a trigger 28 pivoted at 29 on the ribs 21 above the said lever 25. The trigger 28 comprises a cam 30 adapted to project from the box 13 through an opening 31 formed in the 40 cover 17. Any suitable means, such as a screw and lock nut 32 shown herein as mounted on the lever 25, is provided for adjusting the relative positions of the lever 25 with respect to the trigger 28, and the elevation of the cam 30 above 45 the box cover 17.

Welded or otherwise secured to, or formed on, the rod 10, at a point intermediate its ends, is a short bearing 33 by which the rod 10 is rockably mounted in the channel 11 on a fulcrum 34 50 secured therein. The fulcrum 34 comprises two side pieces 35, 36 for rockably confining the bearing 33, the former being higher than the latter to permit rod 10 to be elevated and moved endwise into the box 13 to provide for the as- 55

sembly thereof with a bolt to be hereinafter described.

A vertically elongated opening 40, similar to the opening 19 in the box 13, is formed in the bolt socket 14 between the ears 15 to permit the other end of the rod 10 to cooperate with a bolt 41 slidably mounted in the socket 14 by engagement with any suitable means, such as a notch or hole 42 formed in the side of the bolt whereby the bolt is moved vertically in the socket, as hereinafter described.

The bolt mechanism above described is adapted to be mounted permanently below the finished surface 45 of the floor 46 and in front of a door 47 mounted by hinges 48 to a frame 49. When so mounted, the door 47 is adapted to be held open by the bolt 41 or the said bolt is adapted to serve as a stop for the door as hereinafter described. It will be understood that the device 20 may be mounted in any suitable way in concrete below a wooden floor with the upper surface of the trigger box 13 and bolt 14 flush therewith, as illustrated in Figure 2, or may be mounted in any type of monolithic floor.

25 An angle plate 50 having a trigger cover 51 is secured to the bottom of the door 47 proximate the hinged edge thereof. A door holder 52 having a plate 53 is secured to the bottom of the door at the edge thereof remote from the hinged edge aforesaid. The holder 52 is provided with a socket 54 adapted to receive the bolt 41, as shown in Figure 3, when the holder is positioned above the same. Means 55 on the side of the holder 52 is provided for carrying a bumper 56 made of any suitable material such that when the door is opened against the bolt 41, as shown in dotted lines in Figure 3, the bumper 56 and bolt 41 will serve as a doorstop. The holder 52 also comprises a plunger 57 and a collar 58 slidably mounted therein and spring means 59 abutting the lower wall of the socket 54 normally urging the plunger upwardly against any suitable cover 61 secured to the top thereof. The lower end of the plunger 57 passes through a 45 hole 62 in the upper wall of the socket 54 whereby the plunger 57 is adapted when the bolt 41 is in position in the socket, to push the bolt downwardly out of engagement with the socket 54 and to a point even with the lower surface of both 50 the holder 52 and plate 53.

In the embodiment of the invention here shown, the bolt mechanism comprising its channel, box and socket means above described as a housing, is disposed in the floor on a line generally normal to the plane of the opening in which the door 47 is mounted and in a plane passing through the hinges 48 mounting the said door for opening and closing movement.

60 Referring now to Figures 4 and 5, it will be understood that as the door 47 is opened the angle plate 50 engages the cam 30 on the trigger 28 and presses the same downwardly with the result that the end 27 of the lever 25 will depress the end of the rod 10 which is disposed in the trigger box 13, rock the rod on the fulcrum 34 and elevate the bolt 41. As here shown, the device is positioned so that the bolt 41 will be elevated above the floor to form a stop for the 65 door as shown in dotted lines in Figure 3 when the door has been moved through an opening movement of approximately sixty-five degrees. When the device is so positioned, it will be understood that the bolt 41 is also adapted to enter 70 the socket 54 and hold the door open after the 75

same has been turned through an opening movement of approximately ninety degrees; the engagement of the bolt and socket being effected by stepping upon the bolt and depressing the same with the foot against the yielding resistance of 5 the rod 10 so that the door and socket can be moved over the bolt whereupon the bolt 41 will be elevated into the socket 54 by the flexibility of the rod 10, hence it may be said that the rod 10 is a preferred embodiment of a yieldable connecting means between the bolt and trigger mechanism.

It will also be understood that my bolt mechanism may be mounted in the floor in front of the wall in which the door 47 is mounted and disposed at an angle of preferably more than ninety degrees with respect to the wall, in which case the bolt 41 will not be elevated by the door until the same has been opened through a correspondingly greater angle, and with the further result 20 that the doorstop and holder is thereby adapted to stop and hold the door in open position after the same has been turned through an opening movement of more than ninety degrees.

When it is desired to release the door holder, 25 as shown in Figure 3, the plunger 57 is depressed by the foot until the bolt is flush with the floor and the door closed in the usual way.

From Figures 2 and 5 it will be seen that the trigger cover 51 is a rigid structure forming a 30 part of the plate 50 and prevents the operation of the cam 30 to elevate a bolt 41 when the door is closed, as well as precluding one from tripping over the cam.

If it is desired to mount the mechanism above 35 described for operation with a door hinged at the right-hand edge thereof, that is, on the edge remote from that shown in Figure 1, the box 13 may be inverted and secured as above described to the channel 11 by means of the ears 15 so as to extend to the other side of the channel 11. It has been described above that the cover 17 and plate 18 are constructed to be removably and interchangeably secured to the top or bottom of the box 13. It will also be understood that the 40 ears 15 above described are centrally positioned on the side of the box 13 so that the box may be assembled to the channel in a manner which will permit the box to extend either to the right or left thereof as desired. The only other change 45 in the assembly of the mechanism whereby the same will be adapted for use with a right hand door as distinguished from a left hand door, here shown, would be to invert the plate 20 and its 50 associated parts above described, so that the trigger mechanism would at all times extend through the top of the box irrespective of the side from which the same projects from the 55 channel 11.

Various modifications in the configuration, 60 composition and disposition of the component elements which in combination constitute my improved doorstop and holder may occur to those skilled in the art, hence the foregoing description 65 of my invention is intended as an aid in understanding the terminology of the appended claims and not to unnecessarily limit the same.

What is claimed is:

1. A mechanism of the class described, comprising stop means adapted to be mounted in a floor for movement to an operative position above the surface of the floor from an inoperative position flush with the said surface thereof, in combination with means operable by a door with 70

75

which the same is adapted to be associated for moving said stop means from inoperative position to operative position when said door is open, said operable means comprising connecting means 5 sufficiently yieldable to permit the stop means to be forced downwardly at the will of an operator from operative to inoperative position without otherwise moving said operable means.

2. A mechanism of the class described, for use 10 with a door mounted in a doorway for opening and closing movement, comprising stop means for the door mounted in a floor for movement to an operative position above the surface of the floor from an inoperative position flush with the said 15 surface thereof, in combination with means operable by the door for moving said stop means from inoperative position to operative position and return when said door is opened and closed, said operable means comprising connecting means 20 sufficiently yieldable to permit the stop means to be pressed downwardly at the will of an operator from operative to inoperative position while the door is open to effect a holding engagement between said door and the stop means upon a 25 further opening movement of said door and upon the return of said connecting means to the position from which an operator may have caused it to yield.

3. A doorstop and holder mechanism of the 30 class described comprising in combination a bolt socket and a trigger box connected by means of an elongated housing forming a unit adapted to be mounted beneath the surface of a floor with the top of the socket and box flush with the surface 35 of the floor, said trigger box and housing being operably engageable in either of two positions depending upon whether said unit is for use with a door hinged at either the right hand or left hand edge thereof, a rod fulcrumed in 40 said housing with one end thereof extending into said trigger box and the other end extending into said bolt socket, a bolt in said socket cooperating with one end of said rod, and trigger means in said box cooperating with the other end of 45 said rod, said trigger means being adapted for operable engagement by a door with which the mechanism is associated, whereby the bolt may be moved from inoperative to operative position by said trigger means to serve as a stop or holder 50 for the door.

4. A door stop and holder mechanism of the 55 class described comprising in combination an elongated housing means, motion transmitting means operably mounted in said housing means, doorstop and holder means cooperating with one end of said transmitting means, and trigger means cooperating with the other end thereof, said trigger means and motion transmitting

means being operably engageable in either of two positions depending upon whether said mechanism is for use with a door hinged at either the right hand or left hand edge thereof, said housing being adapted to be mounted in a 5 floor at an angle with respect to a door mounted in a doorway and with said doorstop and holder means located remote from the doorway and occupying an inoperative position flush with the surface of the floor proximate said doorway; said 10 trigger means being adapted for operable engagement by the door with which the said mechanism is associated, whereby the opening movement of said door is adapted to actuate said trigger means and move the doorstop and 15 holder means into operative position above the floor.

5. A doorstop and holder mechanism of the 20 class described comprising in combination an elongated housing means, a yieldable rod fulcrumed in said housing means, a bolt cooperating with one end of said rod, and trigger means 25 cooperating with the other end thereof, said housing being adapted to be mounted in a floor at an angle with respect to a door mounted in a doorway and with said bolt located remote from the doorway and occupying an inoperative position flush with the surface of the floor proximate said doorway; said trigger means being adapted 30 for operable engagement by the door with which the said mechanism is associated, whereby the opening movement of said door is adapted to actuate said trigger means and elevate said bolt into operative position above the floor.

6. A doorstop and holder mechanism of the 35 class described comprising in combination a bolt socket, and a trigger box, connected by means of a housing forming a unit adapted to be mounted in the floor with the top of the socket and the top of the box flush with the surface of the floor; 40 a yieldable rod fulcrumed in said housing with one end thereof extending into said trigger box and the other end extending into said bolt socket, a bolt in said socket flush with the surface of the floor and cooperating with one end of said 45 rod, and trigger means in said box cooperating with the other end of said rod, said rod and trigger means being adapted for movement by the opening movement of a door with which the said mechanism is associated to actuate a bolt 50 and move the same from an inoperative position flush with the surface of the floor to an operative position above the floor, and said rod being adapted to yield and permit the depression of the bolt from operative to inoperative position 55 while said trigger means is maintained in the position to which it was operated by said door.

VINCENT IARROBINO.
